W. E. CHENOT,
APPARATUS FOR MAKING MOTOR FUELS.
APPLICATION FILED FEB. 26, 1917.

1,385,860.

Patented July 26, 1921.

UNITED STATES PATENT OFFICE.

WILLIAM E. CHENOT, OF BELLEVILLE, ILLINOIS.

APPARATUS FOR MAKING MOTOR-FUELS.

1,385,860.

Specification of Letters Patent. Patented July 26, 1921.

Application filed February 26, 1917. Serial No. 151,055.

To all whom it may concern:

Be it known that I, WILLIAM E. CHENOT, a citizen of the United States, residing at Belleville, Illinois, have invented a certain 5 new and useful Improvement in Apparatus for Making Motor-Fuels, of which the following is a full, clear, and exact description, such as will enable others skilled in the art to which it appertains to make and use the 10 same.

This invention relates to an apparatus for making motor fuels, and has for its main object to provide a saturater of novel construction that will thoroughly break up and 15 mix or combine liquids that are used in the manufacture of motor fuel.

The figure of the drawings is a vertical sectional view, partly diagrammatic, of an apparatus equipped with a saturater constructed in accordance with my invention. Said apparatus comprises an agitator A provided with a closed top or cover 1 that can be removed, a filter B that is partially 20 filled with a filtering substance 2, and a saturater or mixer C, which is so constructed that it will effect a thorough, homogeneous and stable incorporation or saturation of the ingredients used in the manufacture of motor fuels. The agitator A is of ordinary 25 construction, except that it is equipped with a closed top or cover 1. It is provided with a pipe 3 through which gasolene, naphtha or kerosene hydrocarbons can be admitted to the agitator, and said agitator 30 is provided at its upper end with a pipe 4 that leads to a condenser 5, which, in turn, is connected by means of a pipe 4^a with a storage tank 6. Said agitator is provided with the usual air supply pipe 7, through which 35 air under pressure can be admitted to the agitator while treating gasolene, naphtha or kerosene in the agitator, and the usual treating solution pipes 8 are provided at the lower end of the agitator for introducing a 40 treating solution or solutions into the agitator, such, for example, as water, acid or alkali. The lower end of the agitator is provided with the usual three-way discharge valve 100 equipped with extensions 100^a, 100^b and 100^c to which pipes or conduits can 45 be coupled, depending upon the position of the valve. If it is desired to draw off the sediment that collects in the agitator the valve 100 can be arranged in such a position that the sediment will be discharged 50 through the extension 100^b. If it is desired to re-run the treated oils through the still a conduit can be coupled to the extension 100^a and the valve 100 can be arranged in such a 55 position that the gasolene, naphtha or kerosene hydrocarbons, after passing through the agitator and being subjected to treatment therein, will be conducted back to the still and redistilled or run through the still again, as is common practice in the manufacture of naphtha. The remaining branch 60 100^c of the valve 100 is used when it is desired to conduct the treated oils from the agitator A to a storage tank or to the filter 65 perviously referred to. When operated in this manner a conduit 100^d is coupled to the extension 100^c of the valve 100 and to a discharge pipe 9 that leads to a gasolene storage tank D. Said discharge pipe 9 is provided with a branch 10 that enters the upper 70 end of the filter B, which branch is provided with a valve 10^a. The discharge pipe 9 is also provided with a valve 9^a that is arranged between the branch 10 and the gasolene storage tank D. At a point intermediate 75 the branch 10 and the valve 9^a a second branch 11 leads from the discharge pipe 9 to a kerosene hydrocarbon storage tank E. The filter B is provided with a discharge pipe 12 that leads from the lower end of 80 the filter B to the gasolene storage tank D, and said discharge pipe 12 is connected by means of a branch 13 with the kerosene hydrocarbon storage tank E, the branch 13 being provided with a valve 13^a, and the pipe 12 being 85 provided with a valve 12^a that is located between the branch 13 and the tank D. The tanks D and E are provided with discharge pipes 14 and 15, respectively, that lead to a mixing pipe 16 which discharges its contents 90 into the saturater C, the pipes 14 and 15 being provided with controlling valves 14^a and 15^a, respectively, and the mixing pipe 16 being provided with an ether supply pipe 17 that is equipped with a controlling valve 17^a. The saturater C preferably consists of a vertically-disposed shell provided with horizontally-disposed screens of fine mesh material, and revolving devices arranged in such 95 a manner that the ingredients, when introduced in the desired proportions into the upper end of the saturater, will be thoroughly broken up and completely mixed or combined while they are traveling through the saturater from the upper to the lower end of 100

110

same. In practice the outer shell 18 of the saturator C is preferably made of approximately the same diameter or cross-sectional area as the pipe 16 through which the ingredients are introduced into the saturator, and a number of horizontally-disposed screens 19, or pieces of fine mesh material, are arranged in the upper portion of the shell 18 above revolving devices provided 10 with spiral blades or vanes 20 which are so arranged that they will revolve when a liquid substance flows from the pipe 16 into the saturator. As the figure of the drawing is partly diagrammatic, I have shown the 15 pipe 16 as being much smaller than the shell 18 of the saturator, but in actual practice said shell and pipe have practically the same diameter.

In the saturator herein shown two oppositely-revolving devices are arranged in the shell 18 of the saturator, each of said devices comprising a vertically-disposed spindle or center portion 21 to which the spiral blade or vane 20 is connected, pieces 25 of screen or gauze 22 being connected to said blade in such a manner that the material that strikes the vane and passes off of same will pass through the gauze 22 and be thoroughly broken up into small particles. The 30 saturator can be provided with any desired number of rotatable mixing devices of the character above referred to, and if desired, screens or layers of gauze 23 of finer mesh than the screens 19 at the upper end of the 35 saturator can be arranged underneath the revolving mixing devices. The various parts of the apparatus can be so arranged that the materials will flow by gravity from one part to another, or pumps 24 of any suitable kind 40 can be arranged in the various pipes that connect the different parts of the apparatus together.

When the apparatus is used for treating gasoline, gasoline is supplied through the 45 pipe 3 to the agitator A, wherein it is subjected to the usual treatment to bring it up to market requirements. The light vapors that are driven off during this treatment are conducted from the upper end of the agitator 50 through the pipe 4 to the condenser 5, wherein they are converted into liquid form and then run to the storage tank 6. If said 55 condensed hydrocarbons are too offensive in odor to be used in this condition, they can either be mixed with treated gasoline, or they can be run into the tank of crude oils next to be refined.

The gasoline can be run directly from the agitator A to the storage tank D, or it can 60 be run from the agitator through the filter B and then through the discharge pipe 12 to the storage tank D.

The apparatus above described can be used for producing a motor fuel composed of 65 gasoline mixed with kerosene hydrocarbons

or kerosene distillates. When used for this purpose gasoline is run through the agitator and then into the storage tank D or from the agitator through the filter B and then through the storage tank D in the manner 70 previously described. Kerosene hydrocarbons or distillates are then introduced into the tank E, and subsequently, these two ingredients, namely, the gasoline and the kerosene hydrocarbons, are thoroughly mixed 75 and combined in the saturator C.

To obtain the hydrocarbons used in the said motor fuels, it is preferable to make the end point for gasoline about 55 B. in the stream, by employing distillation. The oils 80 remaining in the still will be run as for producing kerosene hydrocarbons, preference being given the cracking process, and run down to the end point indicated by refining practice. This method results in a high and 85 low grade fuel, the desired intermediate grades being produced by employing certain proportions of the high grade with the desired proportions of low grade by running through my saturator. After completing the 90 run, the distillates are subjected to treatment in the agitator A, so as to comply with market requirements, the light hydrocarbons that are driven off during this treatment being subsequently liquefied in the condenser 95 5 and then run into the storage tank 6. The gasoline and kerosene hydrocarbons are drawn from the tanks D and E and thoroughly mixed in the saturator C. If a particularly volatile fuel is desired, namely, fuel 100 that is well adapted for use in an aeroplane motor, or where perfect ignition is essential, the requisite quantity of ether can be admitted to the mixing pipe 16 that leads to the saturator C by opening the valve 17^a in 105 the ether supply pipe 17 more or less. By manipulating the valves 14^a and 15^a in the supply pipes that lead to the mixing pipe 16, the proper proportions of the two ingredients can be accurately controlled, so as 110 to produce a motor fuel having the proper requisites for the purpose for which it is intended. While it is immaterial what particular kind of process is used for producing the gasoline or the kerosene hydrocarbons, 115 it is preferable that a cracking process be used in producing the kerosene hydrocarbons, as hydrocarbons produced by such a process are altered, decomposed to some extent and have lighter gravity and higher 120 Baumé density, thus rendering them more volatile and better adapted for use in motor fuels. In the usual cracking process the kerosene hydrocarbons that are produced have a rather offensive odor and contain 125 more or less greasy matter, but this objectionable characteristic of such kerosene hydrocarbons is overcome by my apparatus, owing to the fact that the gasoline and kerosene hydrocarbons are so thoroughly mixed 130

together in the saturator that the greasy matter in the hydrocarbons is dissolved and the objectionable odors lessened.

Having thus described my invention, what I claim and desire to secure by Letters Patent, is:

1. In an apparatus for making motor fuels, a saturator comprising a vertically-disposed, tubular shell adapted to have liquid introduced into the upper end of same, a plurality of rotatable devices in said shell arranged one above the other and provided with spiral blades arranged so that said devices will be revolved in opposite directions by the passage of the liquid through the shell, and screens arranged so that the liquid will pass through same before striking said rotatable devices.

2. In an apparatus for making motor fuels, a saturator comprising a vertically-disposed shell adapted to have liquid introduced into the upper end of same, horizon-

tally-disposed screens arranged inside of said shell adjacent the upper and lower ends of same, and a plurality of rotatable devices arranged inside of said shell between said screens and provided with spiral blades disposed so that the liquid passing downwardly through said shell will cause said devices to revolve in opposite directions.

3. In an apparatus for making motor fuels, a saturator comprising a vertically-disposed shell adapted to have liquid introduced into the upper end of same, and a plurality of rotatable devices arranged inside of said shell one above the other and each composed of a vertically-disposed shaft equipped with a spiral blade having pieces of gauze connected thereto, the blades of said devices being so arranged that the passage of the liquid through the shell will cause said devices to revolve in opposite directions.

WILLIAM E. CHENOT.
